CLAIM

The ornamental design for a lift rail extrusion for a window, as shown and described.

DESCRIPTION

FIG. 1 is a front elevational view of a lift rail extrusion for a window showing my new design;

FIG. 2 is a top plan view thereof;

FIG. 3 is a rear elevational view thereof;

FIG. 4 is a bottom plan view thereof;

FIG. 5 is an end elevational view thereof; and,

FIG. 6 is a perspective view thereof.

*Fig. 4.**Fig. 3.**Fig. 2.**Fig. 1.**Fig. 5.*Fig. 6.
